UNITED STATES PATENT OFFICE.

FREDERICK WATERHOUSE, OF WALLINGFORD, CONNECTICUT, ASSIGNOR TO
R. WALLACE & SON MANUFACTURING COMPANY, OF SAME PLACE.

DESIGN FOR A SPOON OR FORK HANDLE.

SPECIFICATION forming part of Design No. 13,981, dated June 12, 1883.

Application filed April 27, 1883. Term of patent 7 years.

To all whom it may concern:

Be it known that I, FREDERICK WATERHOUSE, of Wallingford, in the county of New Haven and State of Connecticut, have invented a new Design for a Spoon or Fork Handle; and I do hereby declare the following, when taken in connection with the accompanying drawing and the letters of reference marked thereon, to be a full, clear, and exact description of the same, and which said drawing constitutes part of this specification, and represents a face view of the handle.

This invention relates to a design for the ornamentation of spoons, forks, and like articles of table-service; and it consists in the ornamentation of the surface of the handle, as shown in the accompanying illustration and more fully hereinafter described. The handle gradually expands from the bowl toward the end and terminates in a segment shape, the edge of the handle bordered by a plain bead. About midway of the length of the handle is

a rose ornament, *a*. On the face of the handle, within the bead and above the rose, is a plain shield, *b*, and from this shield springs a 25 tracery of scroll-work both upward and downward, and in the tracery above the shield is the representation of a dragon, as shown in the accompanying illustration.

I claim—

The herein-described design for a spoon or fork handle, consisting of the gradually-expanding handle, segment-shaped at the top, its edge bordered by a plain bead, and on the face a plain shield, *b*, with a scroll-work tracery 35 springing from the shield both upward and downward, and the representation of a dragon in the tracery above the shield, as shown and described.

FREDK. WATERHOUSE.
